(57) **CLAIM**

The ornamental design for a hanger, as shown and described.

DESCRIPTION

FIG. 1 is an oblique perspective view of an hanger showing our new design, in accordance with one embodiment; FIG. 2 is a front elevation view thereof;

FIG. 3 is a left side elevation view thereof;

FIG. 4 is a right side elevation view thereof;

FIG. 5 is a rear elevation view thereof;

FIG. 6 is a top plan view thereof; and

FIG. 7 is a bottom plan view thereof;

FIG. 8 is an oblique perspective view of an hanger showing our new design, in accordance with another embodiment;

FIG. 9 is a front elevation view thereof;

FIG. 10 is a left side elevation view thereof;

FIG. 11 is a right side elevation view thereof;

FIG. 12 is a rear elevation view thereof;

FIG. 13 is a top plan view thereof; and,

FIG. 14 is a bottom plan view thereof.

In all figures, solid line shading is used to better illustrate the three-dimensional ornamental features of the design.

The lightweight broken lines are included to show unclaimed subject matter and to delimit claimed solid line portions of the design from unclaimed subject-matter.
